CLAIM

The ornamental design for an electrical connector, as shown and described.

DESCRIPTION

FIG. 1 is a top, right, front perspective view of an electrical connector showing the new design;

FIG. 2 is a top, front and right side perspective view thereof;

FIG. 3 is a top, rear and left side perspective view thereof;

FIG. 4 is a bottom, front and right side perspective view thereof;

FIG. 5 is a bottom plan view thereof;

FIG. 6 is a top plan view thereof;

FIG. 7 is a left side elevation view thereof;

FIG. 8 is a right side elevation view thereof;

FIG. 9 is a rear elevation view thereof; and,

FIG. 10 is a front elevation view thereof.

The broken lines shown represent the portions of the electric connector that form no part of the claimed design.
